Patented May 21, 1901.

T. McCORMICK.

CARBURETER.

(Application filed May 18, 1900.)

UNITED STATES PATENT OFFICE.

THOMAS McCORMICK, OF MOUNT PLEASANT, PENNSYLVANIA, ASSIGNOR OF THREE-FIFTHS TO ANANIAS D. MILLER, OF SAME PLACE; SAMUEL J. MILLER, OF BISBEE, ARIZONA TERRITORY; E. J. KENT AND JOSEPH J. WESLING, OF PITTSBURG, PENNSYLVANIA, AND ADAM G. INNIS, OF COLUMBUS, OHIO.

CARBURETER.

SPECIFICATION forming part of Letters Patent No. 674,812, dated May 21, 1901.

Application filed May 18, 1900. Serial No. 17,131. (No model.)

To all whom it may concern:

Be it known that I, THOMAS McCORMICK, a citizen of the United States, residing at Mount Pleasant, in the county of Westmoreland and State of Pennsylvania, have invented a new and useful Gas-Generator, of which the following is a specification.

My present invention relates to a novel gas-generator of that type designated by the term "carbureters," which type is distinguished by a receiver or chamber containing a hydrocarbon through which air is led for the purpose of obtaining an inflammable gas or carbureted air. In gas-machines of this type great difficulty is encountered in securing precisely such proportions of the air and hydrocarbon as will be productive of the best results; and the object of my invention is to embody in an apparatus of this character certain novel features which will not only enable me to obtain the proper degree of enrichment of the air, but which will insure the constant maintenance of the proper proportions while the machine is in operation.

To the accomplishment of this end and others subordinate thereto the invention consists in providing a plurality of carbureting-chambers, preferably two in number, within the first of which the air is carbureted and is passed as a gas to a second carbureting-chamber for further enrichment, but designed to be saturated or carbureted to a very high degree within a carbureting-injector located within the gas-induction pipe at a point intermediate of the two chambers.

The invention further consists in providing heating-drums within the carbureting-chambers and a superheater located beyond the last chamber and designed to completely gasify any liquid which may pass from the last carbureting-chamber on its way to the point of use.

The invention consists still further in certain features of construction and arrangement, all of which will hereinafter more fully appear, will be illustrated in the accompanying drawings, and succinctly defined in the appended claims.

In said drawings, Figure 1 is a sectional view, partly in elevation, of my apparatus 50 complete; and Fig. 2 is a detail view of the injector-nozzle.

Referring to the numerals of reference employed to designate corresponding parts in both views, 1 and 2 indicate a pair of carbureting-chambers of any desired form and size, and 3 indicates an air receiver or reservoir from which air is supplied through an air-induction pipe 4 to the interior of the chamber 1, the pipe 4 terminating at a point just 60 above the bottom of the chamber and being controlled adjacent to the receiver 3 by an air-supply valve 5. The lower end of the air-induction pipe 4 is submerged in a suitable hydrocarbon 6, supplied to the chamber 1 in 65 suitable quantity through a filling-opening 7, closed by a screw-cap 8. The air let into the chamber 1 from the air-receiver 2 through the pipe 4 is liberated below the surface of the hydrocarbon and ascends in a more or 70 less gasified condition to the gas-space 9, defined above the liquid-level. The gas thus formed passes from the chamber 1 through a gas-eduction pipe 10, controlled by a gas-eduction valve 11, to the interior of the injector-coupling 12, and thence into the gas-induction pipe 13, screwed into the coupling 12 and extended through the top of the chamber 2 to a point adjacent to the bottom 75 of the chamber, the lower or inner end of 80 the pipe 13 being closed and provided above the closure with a series of diminutive lateral openings 14, which render the lower end of the pipe foraminous and cause the gas to be projected in fine jets into the body of the 85 hydrocarbon 15 within the second carbureting-chamber 2. From the last chamber of the series—that is to say, from the chamber 2 in the illustrated embodiment of the invention—the carbureted air or gas passes 90 through a gas-eduction pipe 16 to a superheater 17 of any approved construction arranged to supply the gas generated by the machine to the service-pipe 18, which leads to the burners, explosion-chambers, or other forms 95 of converting devices designed for the utili-

zation of the gas for heating, lighting, or power purposes.

The device as described constitutes the broadest embodiment of the invention, since it comprehends a series of carbureting-chambers, into certain of which the partially-carbureted air is projected in a finely-commi-nuted form and from which the gas is passed to a superheater designed to raise the tension of the gas and to volatilize any liquid which may have been suspended by the gas, and which were it not for the superheater would be passed into the system of service-pipes. I prefer, however, to insure the more or less complete saturation of the air by arranging a hydrocarbon-injector in the gas-conduit through which the carbureted air or gas passes from the chamber 1 to the chamber 2. I therefore extend a liquid-eduction pipe 19 through the top of the chamber 1 from a point below the level of the hydrocarbon 6 and screw the extremity of its horizontal branch 20 into the end of the coupling 12 opposite to and in axial alinement with the gas-induction pipe 13 and 25 communicating with an elongated injector-nozzle 21, screwed at one end into a transverse diaphragm 22 of the coupling, and provided at its opposite extremity, which is located within the pipe 13, considerably in advance 30 of the pipe 10, with a screw-cap 23, having a diminutive axle-jet opening 24, through which the hydrocarbon is projected in a fine spray under the pressure of the gas within the chamber 1, and under the injective action or suc-35 tion produced by the passage around the nozzle of the gas flowing under pressure from the chamber 1 to the chamber 2, through the gas-induction pipe or conduit 13. The horizontal branch 22 is provided with a valve 25, con-trolling the supply of fluid to the injector, it 40 being understood that the valves 11 and 25 constitute the gas and liquid valves of the hydrocarbon-injector for the purpose of regu-lating the proportions of gas and liquid pass-45 ing into the injector, and thereby determining the extent of the carbureting action at this point in accordance with the uses for which the gas is intended, it being well understood in the art that gases of different tensions are 50 required for lighting, heating, and explosive purposes.

It is well understood that the volatilization of the hydrocarbon is necessary to effect its union with the air, and I therefore employ a heating-drum within each of the chambers and preferably extending the entire length of the chambers, as illustrated in the drawings. The primary heating-drum, located in the chamber 1, is indicated by the numeral 26, and the secondary drum, located in the chamber 2, is indicated by the numeral 27. The particular heating agent employed in these heating devices is not essential to their ef-fective utilization; but I prefer to supply 65 them with either steam or hot water, and for this reason their lower ends are connected, through supply-pipes 26' and 27', with the op-

posite ends of a primary heater 28, located outside of and preferably immediately below the chambers 1 and 2 and comprising a wall 70 or casing having a combustion-cavity 29 in its under wall, from which extend vertically through the chamber a number of flues 30, which permit the ready escape of the products of combustion from a burner 31 and also in-crease the effective heating area of the heater. The burner 31 of the primary heater and the burner 32 of the superheater may be arranged and supplied with fuel in any suitable manner; but I prefer to feed them from a gas-supply or burner pipe 33, which leads from the superheater, and thereby utilizes the advance gas circulation for the purpose of heating itself at several points between the gas-inlet and that point of the circulation which 85 is tapped for the supply of the burners. In other words, by utilizing the gas from the superheater for supplying the burners the entire device is rendered self-contained and entirely automatic in its operation. It will now 90 be seen that the arrangement of the heating-drums within the carbureting-chambers will cause more or less expansion of the carbureted air or gas above the fluid-levels and will increase to a greater or less extent the 95 pressure exerted by the gas upon the hydrocarbons and also within the injector, thereby tending to increase the circulation of the gas and liquid and the efficiency of the appa-ratus.

It is sometimes difficult to obtain such fine adjustments of the valves 11 and 25 as will insure the constant equalization of pressures and liquid-levels in the two carbureting-chambers, particularly when the machine is 105 taxed to its utmost capacity by the converting devices which it supplies with fuel. I have therefore provided what I will term "equalizing-pipes" 34 and 35, which extend downwardly through the top wall of each tank and terminate below the level of the hydrocarbon therein, the upper ends of these pipes being normally connected by a suitable pipe or conduit, which for convenience is a flexible hose 36, permanently attached to the 110 upper end of the pipe 35 and designed to be detachably connected to the upper end of the pipe 34 or to a nipple 37, projecting from the receiver, the upper end of the pipe 34 being closed by a screw-cap 38 when the hose 36 is 115 disconnected therefrom. The lower end of the pipe 35 is preferably closed and provided, like the pipe 13, with a foraminous portion 39.

The operation of my device is as follows: Assuming the several valves to be open and the burners 31 and 32 to be in action, air is supplied under pressure from the receiver or reservoir 3 through the air-induction pipe 4 and is liberated below the surface of the hydrocarbon within the carbureting-chamber 1. The more or less carbureted air arising from the body of hydrocarbon to the upper end of the chamber escapes under more or less pres-130 sure through the gas-eduction pipe 10 to the

interior of the injector-coupling 12, from whence it passes into the gas-induction pipe of the chamber 2 and around the injection-nozzle 21 of the hydrocarbon-injector. Under the pressure of the gas within the chamber 1, which pressure is somewhat increased by the expansive influence exerted by the presence of the heater 26, hydrocarbon is forced from the bottom of the chamber 1 through the liquid-eduction pipe 19 into the hydrocarbon-injector nozzle 21, the raising of the hydrocarbon into the injector being assisted, and in some instances actually produced, by the injective action of air passing around the nozzle and into the chamber 2 through the liquid-induction pipe 13. As the hydrocarbon is projected from the minute opening 24 in a fine spray it is taken up by the partially-carbureted air or gas, which is thus carbureted to a still further degree and in this enriched condition is projected laterally in the body of hydrocarbon 15 through the openings 14 in the lower end of the gas-induction pipe. It may be noted in passing that the air is first carbureted in the chamber 1, then circulates through a conduit intermediate of the chambers, where it is subjected to the injection of a fine spray of liquid and is then itself in a more or less enriched condition projected in a finely-communited state into a body of hydrocarbon, the peculiarity to which attention is especially called being the successive projection of the fluid into the gas and next of the gas into the fluid. Returning now to the operation, the gas rising into the upper portion of the chamber 2 escapes through the eduction-pipe 16 into the superheater, where its tension is raised and where the complete volatilization of any suspended fluid is effected to prevent the usual accumulation of oil within the service-pipes of a gas-supply system.

If desired, a suitable indicator 40 may be mounted upon the superheater for the purpose of indicating the pressure and the enrichment of the gas.

It has heretofore been stated that the hose 36 is under some circumstances detached and is connected to the nipple 37 upon the air reservoir or receiver 3. This is only done when under comparatively extraordinary conditions it is necessary to obtain a greater predominance of air within the chamber 2, the proper proportions of air and hydrocarbon being ordinarily obtained by the adjustment of the valves 11 and 25 and by the automatic equalization maintained by the equalizing-pipes 34 and 35, connected by the conduit or hose 36.

From the foregoing it will be observed that I have produced a simple, ingenious, and efficient gas-making apparatus or generator of that type known in the art as "carburetors;" but while the present embodiment of the invention is believed to be preferable, I desire to reserve the right to effect such structural changes and variations as may be suggested

by experience and experiment and which may come properly within the scope of the appended claims.

70

What I claim is—

1. A gas-making machine of the character specified comprising a plurality of carbureting-chambers adapted to contain a hydrocarbon, means for leading air through said chambers, a separate and independent secondary heater located in each chamber and extending from end to end thereof, and a primary heater having direct connection with each of the secondary heaters at a point exterior to the chambers.

75

2. A gas-making machine of the character specified comprising a plurality of carbureting-chambers adapted to contain a hydrocarbon, means for leading air through said chambers, a separate and independent secondary heater located in each chamber and extending from end to end thereof, a primary heater having direct connection with each of the secondary heaters at a point exterior to the chambers, a burner located below the primary heater, and means for leading gas from the machine for consumption at said burner.

85

3. A gas-making machine of the character specified comprising a plurality of carbureting-chambers adapted to contain a hydrocarbon, means for leading air through the several chambers successively, a superheater arranged to receive the gas from the last chamber, a secondary heater for each of the chambers, a primary heater common to the several secondary heaters, burners arranged in effective proximity to the primary heater and superheater, respectively, and means for supplying said burners with gas from the superheater.

95

4. A gas-making machine of the character specified comprising a plurality of chambers each adapted to contain a hydrocarbon, a conduit leading from one chamber at a point above the hydrocarbon and discharging into the body of hydrocarbon contained in the other chamber, and means for injecting a hydrocarbon in comminuted form into the conduit at a point intermediate of the chambers, whereby the air or gas passed through the chambers for successive enrichment, is subjected to an enriching jet of hydrocarbon at a point intermediate of the chambers.

100

5. A gas-making machine of the character specified comprising a chamber adapted to contain a hydrocarbon, a conduit leading to said chamber and provided at its lower end with means for discharging a gas in a finely-comminuted form into the body of hydrocarbon, means for supplying air or gas to the conduit, and means for projecting a jet of hydrocarbon into the conduit, whereby the air or gas passing to the carbureting-chamber receives an injection of hydrocarbon and is subsequently itself injected into a body of hydrocarbon.

115

6. In a gas-making machine of the character specified, the combination with a plural-

120

125

130

ity of carbureting-chambers each adapted to contain a hydrocarbon, of a gas-conduit leading from one chamber at a point above the hydrocarbon and having a foraminous extremity located below the surface of the hydrocarbon in the other chamber, a liquid-eduction pipe extending from a point below the surface of the hydrocarbon in one receptacle, and a reduced nozzle communicating with the liquid-eduction pipe and extending into the gas-conduit to permit the injection of a spray of hydrocarbon into the more or less carbureted air passing through the conduit from upper part of the first chamber and designed to be projected in minute jets through the foraminous end of the conduit located below the hydrocarbon in the other chamber.

7. In a gas-making machine of the character specified, the combination with a plurality of carbureting-chambers each adapted to contain a body of hydrocarbon, of means for leading air through said chambers for enrichment, and intercommunicating equalizing-pipes opening into said chambers below the surface of the hydrocarbon, whereby approximately identical liquid-levels will be maintained in the several chambers.

8. In a gas-making machine of the character specified, the combination with a pair of carbureting-chambers adapted to contain a hydrocarbon, of a heater located within each chamber, a gas-conduit leading from the upper part of one chamber and discharging below the surface of the hydrocarbon in another chamber, a hydrocarbon-injector located in said conduit, means for leading air under pressure to the first chamber, and means for obtaining identical liquid-levels and gas-pres- 40

ures in the several chambers.

9. In a gas-machine of the character specified, the combination with a plurality of carbureting-chambers adapted to contain a hydrocarbon, and means for discharging air into the body of hydrocarbon in one chamber, of a valve-controlled gas-conduit leading from said chamber and discharging below the level of the hydrocarbon in the next chamber of the series, a hydrocarbon-injector located 45 within the gas-conduit and supplied with hydrocarbon from the first chamber, a heating-

drum located within each carbureting-chamber, a primary heater exterior to the chambers and arranged to supply a heating agent to the several drums, and a burner located 55 below the primary heater and supplied with gas from the machine.

10. In a gas-machine of the character specified, the combination with a pair of carbureting-chambers adapted to contain a hydrocarbon, an air-reservoir, and a valve-controlled air-induction pipe extending from the reservoir and discharging below the surface of the hydrocarbon in one of the chambers, a valve-controlled gas-conduit leading from the upper part of said chamber and discharging into the body of hydrocarbon in the other chamber, a liquid-eduction pipe extended into the body of hydrocarbon in the first chamber and having an injector-nozzle extending into the 70 conduit intermediate of the chambers, inter-communicating equalizing-pipes located within the chambers and opening below the surfaces of the hydrocarbons therein, a heating-drum located within each chamber, a primary 75 heater exterior to the chambers and common to both drums, a superheater communicating with the gas-space of the last chamber, burners for the primary heater and superheater, respectively, and means for supplying gas to 80 said burners from the superheater.

11. In a gas-making machine, the combination with a pair of chambers each adapted to contain a hydrocarbon, of means for liberating air within one chamber below the liquid-level, a conduit leading from said chamber above the liquid-level and extended into the other chamber below the liquid-level therein and provided with means for injecting the enriched air in comminuted form into the 90 body of liquid hydrocarbon in the last-named chamber, and means for injecting liquid hydrocarbon in comminuted form into the enriched air passing through the conduit.

In testimony that I claim the foregoing as 95 my own I have hereto affixed my signature in the presence of two witnesses.

THOMAS McCORMICK.
